UNITED STATES PATENT OFFICE.

GERTRUDE SHEAR, OF BERGMAN, ARKANSAS.

DARNING IMPLEMENT.

No. 846,253.

Specification of Letters Patent.

Patented March 5, 1907.

Application filed October 3, 1906. Serial No. 337,266.

To all whom it may concern:

Be it known that I, GERTRUDE SHEAR, a citizen of the United States, residing at Bergman, in the State of Arkansas, have invented 5 new and useful Improvements in Darning Implements, of which the following is a specification.

This invention relates to darning implements of the type employed for mending 10 knitted or other fabrics, and has for its objects to provide a comparatively simple inexpensive device of this character whereby the darning operation may be rapidly and effectually performed, one wherein the darning-thread will be properly supplied to the 15 needles while in action, and one which obviates necessity for repeatedly threading the needles as the darning progresses.

With these and other objects in view the 20 invention comprises the novel features of construction and combination of parts more fully hereinafter described.

In the accompanying drawings, Figure 1 is a top plan view of an implement embodying the invention. Fig. 2 is a longitudinal section taken on the line 2 2 of Fig. 1. Fig. 3 is a cross-section taken on the line 3 3 of Fig. 2. Fig. 4 is a perspective view of the thread-holding instrument.

Referring to the drawings, it will be seen 30 that the implement embodies a handle 1, enlarged at its forward end to form a head 2, having flattened side faces and a series of four or more needles 3 fixed at their rear ends 35 in the head to project forwardly therefrom, the outer ends of the needles, which are arranged in spaced parallel relation, as shown, being sharpened or pointed, as at 4, and provided adjacent their pointed ends with elongated thread-receiving eyes 5.

Fixed on the upper side face of the head is 40 a box or casing 6, having an upper hinged lid or cover 7, which may be held in closed position by means of a spring-catch 8, there being formed in the cover a plurality of spaced longitudinal slots 9, arranged, respectively, in axial alinement with the several needles 3, while rotatively mounted in the casing is a series of thread-carrying spools or

bobbins 10, corresponding in number to the 50 number of needles and arranged, respectively, beneath the slots 9, through which the threads from the bobbins are fed to the corresponding needles 3.

Employed in connection with the darning 55 implement and for retaining the threads in the fabric during withdrawal of the needles 3, as will more fully hereinafter appear, is a thread-holding implement or needle 11, preferably of the form illustrated in Fig. 4 and 60 having at one end a finger piece or ring 12.

In practice the bobbins 10 having been filled with darning-thread and arranged in the casing 6, the threads from the bobbins are drawn outward through the overlying 65 slots or openings 9 and threaded through the eyes 5 of the corresponding needles. After the needles have been properly threaded the material of the fabric to be darned and at opposite sides of the worn place is gathered on 70 the needles 3 in accord with the usual method of darning, after which the instrument 11 is engaged beneath and for holding the threads while withdrawing the needles 3 from the fabric, thereby drawing the threads from the 75 bobbins 10 and to extend in parallel relation across the worn place, thus forming the foundation-stitches. After thus performing the first step in the darning operation the threads are cut and the operation continued by working 80 the instrument back and forth through the fabric in the manner above explained, but at right angles to the foundation-stitches in laying the cross-stitches, which are worked alternately above and below the foundation- 85 stitches, as usual in work of this character. It is apparent that as the darning operation progresses the threads will be properly fed from the bobbins to the needles and that the needles need necessarily be threaded but 90 once during the entire darning operation.

Having thus described my invention, what I claim is—

1. A darning instrument comprising a handle, a plurality of needles carried thereby, a 95 casing mounted on the handle and having one of its walls provided with a plurality of openings, and a plurality of thread-carrying

bobbins rotatably mounted in the casing for feeding the threads through said openings to the respective needles.

2. A darning implement comprising a handle, a plurality of forwardly-projecting needles carried thereby, a casing mounted on the handle, a plurality of thread-carrying bobbins rotatably mounted in the casing and a movable cover for the casing provided with

a plurality of longitudinal slots disposed in alignment with the respective needles and constituting guides for the several threads.

In testimony whereof I affix my signature in presence of two witnesses.

GERTRUDE SHEAR.
